ALBERT H. GAESS, OF WATERBURY, CONNECTICUT, ASSIGNOR TO THE E. J. MANVILLE MACHINE COMPANY, OF WATERBURY, CONNECTICUT, A CORPORATION OF CONNECTICUT.

PUNCH-TRANSFER MECHANISM FOR HEADING MACHINES.

Application filed May 24, 1921. Serial No. 472,226.

To all whom it may concern:

Be it known that I, ALBERT H. GAESS, a citizen of the United States, residing at Waterbury, in the county of New Haven and State of Connecticut, have invented a new and useful Improvement in Punch-Transfer Mechanism for Heading Machines, of which the following is a specification.

- 10 In multiple stroke metal heading machines, the stock held by the dies is operated upon successively by different punches. The punches are fixed to a vertically movable slide mounted on a horizontally reciprocating gate, the vertical position of the slide on the gate being changed between the forward movements of the gate to bring the several punches into line with the stock. A machine of this class is illustrated in
- 15 United States patent to Campbell No. 926,170, June 29, 1909. In machines of this type means are usually provided for preventing damage that would result from improper adjustment of the parts or from the 20 accidental interposition of foreign pieces or tools between moving and fixed parts of the punch mechanisms. Means of this character are illustrated in United States patent to Gaess No. 1,372,132, March 22, 1921.
- 25 The present invention relates to the means provided for preventing such injury to these machines, and the object is the construction of a very simple, cheap and effective mechanism for such purpose.
- 30 Previously safety mechanisms of this nature have had the transfer lever, that is positively operated by a cam, made in two sections with a yielding means arranged between and connecting the sections in such
- 35 manner that if the rocker arm that is actuated by the lever for raising and lowering the punch slide is held from movement for any reason on either the forward or backward stroke of the lever, the connection between the cam operated lever sections will
- 40 yield and not force a movement of the rocker against the obstruction, as is shown in applicant's above mentioned patent. In

the new form the transfer lever is made in a single piece and the yielding means is carried thereby and arranged to act between the lever and a part that is connected with the joint between the lever and the rocker which is oscillated by the reciprocations of the lever.

55 In the accompanying drawings, Figure 1 shows a side view of the transfer lever and the rocker arm of a machine of the type referred to provided with an intermediate mechanism which embodies this invention. Fig. 2 shows an end view of the same with portions broken away to show the construction. Fig. 3 is a transverse section on the plane indicated by the dotted line 3—3 on Fig. 1. Fig. 4 is a longitudinal section of the joint end of the lever.

60 The transfer lever 1 shown, has a yoke 2 at one end that is provided with rolls 3 against which the cam runs in the usual manner for reciprocating the lever. The lever near the other end has an opening 4 in which is placed a stiff spiral spring 5 the ends of the spring resting in recesses 65 in the end walls of this opening. A portion of the end walls of this opening on one side are desirably cut away as at 70 75 for facilitating the insertion of the spring. To locate the spring, which may be designed to resist a tension of many thousand pounds 80 in the large machines, in position, the spring is compressed and dropped into the opening from one side and then allowed to expand against the bottom of the recesses 85 in the end walls of the opening.

85 The rocker arm 7 is mounted in the usual way on the end of the rock shaft 8 and in the free end of the rocker arm is an opening 9. In this opening is placed a trunnion bearing block 10. This block is adjusted 90 up and down the opening in the rocker arm by means of screws 11 and 12 and is clamped in position by a nut 13. Extending through a cylindrical opening in this block is the trunnion 14 on the back of the 95 joint or the connection block 15. The

trunnion and joint block are retained in place by a washer 16 and the nut 17 that is screwed on the threaded stem of the trunnion. The joint block 15 lies in an opening 18 in the end of the transfer lever and is free to move back and forth horizontally along this opening. Extending through the joint block 15 is a spindle 19 that is threaded and provided with nuts 20 and 21 on each side of the joint block. This spindle has a reduced section that extends through the spring and its tip 22 projects into a guiding socket 23 in the lever. Near the tip the spindle is threaded and provided with a nut 24 that is designed to bear against a collar 25 which is free to move on the spindle and also free to move in the end wall of the opening 4 in the lever. On the spindle is a shoulder 26 and movable on the reduced portion of the spindle adjacent to this shoulder and loosely held in the end wall of the opening 4 is a collar 27.

In assembling this mechanism the spring is first set in the opening, then the spindle is passed through the block 15 and spring until the shoulder 26 on the spindle pushes the collar 27 against the end of the spring. The nut 24 is then turned up so as to push the collar 25 against the other end of the spring. The tension of the spring is such that during the normal operation of the machine it will hold the spindle and joint block so that as the lever is reciprocated the rocker arm will be oscillated to perform the work required. If for any reason owing to false adjustment of any of the parts or the entry of any foreign material or if a tool gets in the way and the rocker is held or cannot make its full stroke, the spring yields so that no part will be broken by the reciprocations of the lever as it is driven by its cam. When the rocker arm fails to move backward and the lever is drawn backward, the spring is compressed between the collar 25 that is held by the nut 24 on the spindle and the end wall of the recess at the other end of the spring. If the rocker arm is held so that it cannot move forward and the lever moves forward, the spring is compressed between the collar 27 on the spindle and the end wall of the recess in the lever at the other end of the spring. In this form of safety mechanism the lever which forms one element is made as a unitary structure and it carries the spring which forms the second element and also the spindle which forms the third element and is connected with the joint block. This construction is simple to manufacture and is effective in operation.

The invention claimed is:

1. A mechanism for operating the punch transfer slide of a metal heading machine, comprising a transfer lever, a spiral spring carried by the lever, a spindle loosely mount-

ed in the lever and retained from longitudinal movement by the spring, a rocker arm, and means connecting the rocker arm with said spindle, whereby under normal conditions the reciprocation of the lever through the spring reciprocates the spindle and causes the oscillation of the rocker arm, but should the rocker arm be held from movement so that the spindle cannot reciprocate, the spring yields and allows the lever to reciprocate independently of the spindle.

2. A mechanism for operating the punch transfer slide of a metal heading machine, comprising a transfer lever, a spiral spring mounted in an opening in said lever and thrusting against the ends of said opening, a spindle loosely mounted in the lever and having enlargements butting against the ends of the spring, a rocker arm, and means connecting the rocker arm with said spindle whereby under normal conditions the reciprocation of the lever through the spring reciprocates the spindle and causes the oscillation of the rocker arm but should the rocker arm be held from movement so that the spindle cannot reciprocate, the spring yields and allows the lever to reciprocate independently of the spindle.

3. A mechanism for operating the punch transfer slide of a metal heading machine, comprising a transfer lever, a spiral spring mounted in an opening in said lever and thrusting against the ends of said opening, a spindle loosely mounted in the lever and having enlargements butting against the ends of the spring, a joint block movably mounted in an opening in the lever and connected with said spindle, and a rocker arm pivotally connected with said block.

4. A mechanism for operating the punch transfer slide of a metal heading machine, comprising a transfer lever, a spiral spring mounted in an opening in said lever and thrusting against the ends of said opening, a spindle loosely mounted in the lever, collars mounted on the spindle and butting against the ends of the spring, a joint block movably mounted in an opening in the lever and connected with said spindle, a rocker arm, a trunnion block mounted in said arm, and a trunnion extending from said joint block through said trunnion block.

5. A mechanism for operating the punch transfer slide of a metal heading machine, comprising a transfer lever, a spindle supported by and longitudinally movable independently of the lever, a spiral spring carried by the lever and retaining said spindle from moving relatively to the spindle in both directions under normal conditions, and a rocker arm connected to the spindle.

6. A mechanism for operating the punch transfer slide of a metal heading machine, comprising a transfer lever, a spindle sup-

ported by and movable independently of the transfer slide of a metal heading machine, comprising a transfer lever, a spindle loosely 10 mounted in the lever, and a spiral spring mounted in the lever, said spring at each end thrusting against a wall of the lever and a collar on the spindle.

5 under normal conditions, a rocker arm, and a swivel connection between the rocker arm and the spindle.

7. A mechanism for operating the punch

ALBERT H. GAESS.
